AMALGAMATING APPARATUS AND PROCESS

Charles Butters, Berkeley, Calif.

Application September 23, 1932, Serial No. 634,473

6 Claims. (Cl. 209—64)

This invention relates to apparatus and processes for extracting fine gold from beach sand and other gold bearing sands or deposits and the principal object of the invention is to provide 5 improved apparatus operating on a new method which will more effectively recover gold and other values in such deposits by amalgamation, especially what is known as "rusty" or "scaled" gold which does not yield to ordinary methods of 10 amalgamation as heretofore carried out. Another object of the invention is to provide such apparatus and process which may be operated on a very large scale in the commercial recovery of fine gold. Other objects and advantages of the 15 invention will appear in the following specification and accompanying drawing.

In the drawing Fig. 1 is a plan view of one unit of an installation of my improved apparatus.

Fig. 2 is a vertical section through the special 20 riffle construction employed.

Fig. 3 is a cross section of Fig. 2 as seen along the line 3—3 thereof.

Fig. 4 is a plan view of a portion of an amalgamating rod.

25 Briefly described, my invention comprises a battery of special vibratory riffles incorporating means for constantly cleaning or grinding the rusty gold particles and constantly subjecting it to friction against moving amalgamating surfaces in the form of hundreds of small loose rods 30 in the pockets of the special riffle board and which rods may be easily taken out and washed of their accumulated values in warm mercury and replaced.

35 In further detail, Fig. 1 shows a gravity flow shaking table suitably supported or suspended at a slant by means not shown, but well understood in the art, and the table is provided with several dozens of riffle sections or trays 1 fed at the high 40 side by a suitable trough 2 fitted with spouts or side outlets 3 for flow of wet material across the riffle sections in direction of the arrow 4, while means such as the eccentric 5 and rod 6 operating preferably through a resilient link as the 45 spring 7, are provided for driving the table at about from 200 to 350 oscillations per minute in a direction as per double-headed arrow 8 or transversely to the direction of flow of material over the riffles.

50 The body of the table may be of wood as indicated in Fig. 3 at 9, with sides 10 and fitting between which are a plurality of what may be called riffle plates 1 or trays, each preferably about a foot in width and about two to six feet long, provided with a great many pockets 11 extending

transversely to the direction of flow. These riffle plates or trays are preferably of moulded resilient tough rubber with each section in one piece and with the pockets about a half inch more or less in width and depth with rounding bottoms, 60 and partition walls 12 slanting backwardly against the direction of flow as shown in Fig. 2. The angle of the table is about $\frac{3}{4}$ inch per foot and within the pockets of the trays are loose rods 13 of copper with their surfaces amalgamated with quicksilver. These rods are preferably round of about $\frac{1}{8}$ or $\frac{1}{4}$ inch diameter, and they may be roughened or finely threaded or grooved from end to end so as to hold more amalgam as indicated at 14 in Fig. 4, while in 65 length they are about an inch shorter than the length of the pockets, so as to slide back and forth endwise in the pockets and rebound when they strike the rubber end walls of the pockets. I have found one rod in a pocket to be sufficient though 70 more may be used.

The trays may be held in place on the table as by strips of wood nailed to the table between each row, and held from sliding down the slanted deck of the table by any suitable means such 80 as pins 17 (Fig. 3) projecting upward from the table into the upper or both ends of the trays, all so that the trays while fitting snugly in place, may be easily pulled out for emptying or cleaning 85 when desired.

The above proportions and sizes of the members are suggestions merely, by way of preference, and are not to be held limiting in any respect. A feature of importance is to have the rods heavy enough so that due to their inertia 90 they will travel back and forth in the pockets at a different speed than the travel of the sands and hence will set up an abrading or scouring action between the pulp and the rods loosely imbedded therein.

95 Between every ten or more pockets as described is a special grinding pocket of somewhat larger size and fitted with a curved shoe 15 of hard metal, such as hard steel, and loosely positioned in which is a hard metal rod 16 as of steel. This rod is about the length of, but considerably larger, than the copper rods referred to and it works in the hollow of the shoe like a grinding roll so as to effectually grind and brighten any gold particles not caught by the preceding pockets. 100 This rod and thus make this gold readily susceptible to amalgamation in the succeeding pockets.

The table may be run with trays open at the top, or any suitable cover or lid may be provided, a satisfactory means of covering the pulp or wet 110

sand as it flows down over the trays I have found to consist in a sheet of light weight waterproof cloth 18 suspended at the upper end as from a rod 19 in a manner so that the cloth will ride 5 on top of the thin layer of pulp 20 passing over the pockets and thereby effectively reduce the tendency to entrain air, and the possible effect of surface attraction of air for the smaller particles of gold.

10 In operation, the gold bearing sands or material to be treated is screened or otherwise classified, preferably in the so-called wet way with water, and as the gold and other metallic constituents, especially of beach sand, are very fine 15 and flaky, it is important that a well classified feed should be delivered to the table, though in some cases the gold bearing sands have already been so classified by nature as to require very little further classification. The table is kept under 20 vibratory or shaking motion so that the wet mass will flow in an even layer downwardly over the table and the rods are kept properly amalgamated by sprinkling a few drops of fresh mercury 25 into the pockets from time to time to keep the rods from drying out through the accumulation of dry amalgam. A few drops in excess of what is required will do no harm as it can not get out of the pocket. Since the rods lie in the bottom 30 of the pockets they only act on the gold and concentrates and not on the bulk of the material passing over the pockets with a result that a particle of rusty gold caught in any rifle is scoured clean and amalgamated, the sand being constantly further concentrated in each pocket as it 35 passes.

At intervals the material passes through the special grinding pockets fitted with the steel rod and shoe where any exceptionally refractory material is conditioned as previously explained.

40 In cleaning up, and which probably will not have to be done oftener than from one week to four weeks with the average run of material, the table is stopped, the rods are gathered up, trucked to the clean up room and placed in batches in tubes about the length of the rods and 45 warm quicksilver is poured over the rods into the tubes, the covers are clamped on the tubes, and they are revolved in hot water for about ten minutes. The warm quicksilver completely 50 dissolves all of the amalgam. This is poured off and repeated with a second wash, and the quicksilver strained for re-use. The rods are now ready to be replaced. The rods never require dressing as the 55 scouring action of the sand removes any copper oxide which might otherwise form in places.

55 The rubber trays may easily be unhooked from their supporting pins and slipped from the deck and washed clean in a truck or tub and replaced with a set of fresh rods. The operation of cleaning up a whole table of the proportions given 60 could easily be carried out and the table started again in about an hour with the labor of two men, and who would then turn their attention to another table of the installation, so that but one table would be tied up at a time.

65 In describing my improvements as above I do so with full knowledge of previous attempts to use loose devices shaking around on screens to assist amalgamation, also the use of stationary 70 amalgamating rods in the form of a griddle, also rods floating on liquid pools of mercury, but none of these have proven practical, the use of liquid pools of mercury with or without rods entails such an enormous weight as well as expense when 75 used in a battery of tables of any size as to make

it quite out of the question, for if a depth of a half inch of mercury were used it would take about twelve tons per table, whereas I operate with the minimum of quicksilver and constantly keep it bright and receptive. I am also aware 80 of rubber riffle plates having been used, but I believe my use of trays of rubber with pockets having partition and end walls of live rubber, the pockets provided with rounding bottoms in which the rods lie in a manner free to slide and work against the material and subjecting it to sliding friction against the bottom and sides of the pockets, to be new, as well as the stages of more positive grinding at intervals of several 85 pockets by means of the steel rods and shoes. I 90 also believe the process of treatment involved, i. e. the simultaneous grinding, scouring and amalgamating action within a pocket to be new, as well as the treatment of the rods with warm quicksilver to dissolve off the amalgam, and also 95 other phases of the method of treatment described, and therefore I claim:

1. Gold recovery apparatus comprising a concentrating table provided with successive series 100 of longitudinally extending elongated open-top pockets therein, said pockets provided with end and side walls and a bottom all made mercury-tight, a loose amalgamated metal rod lying within and on the bottom of each pocket of a size and length adapted to jiggle around within the 105 pockets when the same are shaken and move longitudinally therein, means for shaking the table in a manner to shake the pockets longitudinally, and means for causing a flow of fine gold carrying material from one side across the 110 pockets and subjecting the material to friction between said loose rods and the inside of the pockets.

2. Gold recovery apparatus comprising a concentrating table provided with successive series 115 of longitudinally extending closed end open-top mercury-tight pockets therein, loose amalgamated metal rods lying within and on the bottom of the pockets adapted to jiggle around within the pockets when the same are shaken, means for 120 shaking the table to shake the pockets longitudinally, and means for causing a flow of fine gold carrying material from one side across the pockets and subjecting the material to friction between said loose rods and the inside of the 125 pockets, said pockets formed of soft resilient rubber with end walls.

3. Gold recovery apparatus comprising a concentrating table provided with successive series 130 of longitudinally extending closed end open-top mercury-tight pockets therein, loose amalgamated metal rods lying within and on the bottom of the pockets adapted to jiggle around within the pockets when the same are shaken, means for shaking the table to shake the pockets longitudinally, and means for causing a flow of fine 135 gold carrying material from one side across the pockets and subjecting the material to friction between said loose rods and the inside of the pockets, said pockets formed of soft resilient rubber and with their separating walls all slanted in a direction opposite to the flow of material.

4. In a structure as specified in claim 1, larger 140 pockets interposed in the series provided with hard metal grinding surfaces between which some of the material passes.

5. In a structure as specified in claim 1, larger 145 pockets interposed in the series provided with hard metal grinding surfaces in the form of a 150

lower curved metal shoe and a metal roller supported with freedom for endwise sliding on the shoe.

6. In a gold concentrator, the combination of 5 mercury-tight round bottom rifle pockets and a loose round amalgamated metal rod freely positioned within each of said pockets of a size and

length adapted for rocking and endwise sliding motion therein, means for vibrating the concentrator to effect endwise sliding movement of the rods in said pockets.
